To all whom it may concern:

Be it known that I, Charles W. Fig. 5 is a front elevational view thereof on a slightly reduced scale, with the frame in closed position.

The characteristic features of the design reside in a handbag frame composed of hinged sections of the configuration and arrangement shown, and held in place in closed position by a clasp having the specific configuration and positioned as illustrated on the drawing.

I claim:

The ornamental design for a handbag frame, substantially as shown and described.

CHAS. W. HARDY.
